REFRIGERATION

Nils Erland af Kleen, Stockholm, Sweden, assignor to Kleen Refrigerator, Inc., Hoboken, N. J., a corporation of Delaware

Application June 2, 1945, Serial No. 597,337

9 Claims. (Cl. 62—5)

1

This invention relates to new and useful improvements in the art of refrigeration and is a continuation-in-part of my application, Serial No. 387,854 filed April 10, 1941, now abandoned.

It is well known in the art of refrigeration that in order to maintain a predetermined temperature in a refrigerator cabinet or the like by means of refrigerating apparatus of the absorption or adsorption type, a certain quantity of refrigerant has to be circulated. As the load on the refrigerating apparatus increases due to placing more comestibles in the cabinet, or to filling the ice trays with water to be frozen, or to rising room or ambient temperature, the rate of circulation of the refrigerant per unit of time must also be increased to maintain the desired temperature in the cabinet.

In view of such varying loads, it has generally been the practice to construct and design the refrigerating apparatus with a predetermined capacity such as to take care of the maximum loads to be encountered and to obtain the highest coefficient of performance of the refrigerating apparatus when operating the latter during such periods of maximum loads or abnormal conditions. However, the maximum capacity of a refrigerating system is only utilized for very short periods during the year with the result that for the greater part of the time the refrigerating system is operated at only a fraction of its maximum capacity. Consequently, the average coefficient of performance of the machine has been comparatively low.

One of the objects of the present invention is to overcome the above noted disadvantages in refrigerating apparatus heretofore employed and to this end the invention consists in constructing and designing the refrigerating apparatus to have its highest or best coefficient of performance when operating at normal loads and in providing means for overloading or increasing the capacity or output per unit of time of certain parts of the refrigerating apparatus so as to take care of the maximum refrigeration demands during the periods of maximum loads.

Another object of the invention is to provide means for varying the heating rate per unit of time of the heating means for that part of an absorption or adsorption refrigerating system in which the refrigerant is generated and also to provide means for varying correspondingly the cooling rate per unit of time of the cooling means for those parts of the refrigerating system in which the refrigerant is condensed or liquefied and is absorbed or adsorbed, respectively, and to control the operation of such rate-varying means in accordance with the demands for refrigeration so as to obtain the highest coefficient of performance of the system when operating under normal conditions.

2

A further object of the invention is to provide means for overloading or increasing the capacity per unit of time of certain parts of absorption or adsorption refrigerating apparatus and to control the operation of said overloading means in accordance with a condition affected by the evaporator and/or a condition affected by the ambient temperature.

The above together with other objects and advantages of the invention will become more apparent as the description proceeds with reference to the accompanying drawings in which

Fig. 1 is a diagrammatic view of intermittent absorption refrigerating apparatus embodying the invention;

Fig. 2 is a similar view of a modification, and
Fig. 3 is a similar view of another embodiment of the invention.

Referring to Fig. 1 of the drawings, the refrigerator diagrammatically illustrated comprises a household refrigerator cabinet 10 having associated therewith an intermittent absorption refrigerating unit constructed and designed in accordance with the invention.

The refrigerating unit comprises a closed system formed by a plurality of interconnected parts including a boiler-absorber or generator-absorber 11 containing strontium chloride or other suitable absorbent capable of absorbing ammonia or other refrigerant fluid employed in the system, a condenser 12 provided with heat dissipating fins and arranged in a flue space or duct F to be cooled by air, a receiving vessel 13 embedded in the thermal insulation of the cabinet 10, and an evaporator 14 located in the thermally insulated storage space 15 of the cabinet 10.

The boiler-absorber 11 is heated by an electrical heating element or other suitable heating means 16 during what is known as the generating period of the unit to drive out or liberate the refrigerant from the absorbent. The refrigerant vapors driven out of the absorbent chamber of the boiler-absorber 11 are liquefied in the condenser 12 and the refrigerant liquid is collected in the receiver 13 and evaporator 14.

When all of the refrigerant that can be utilized for refrigeration purposes has been liberated from the absorbent and collected in the receiver and evaporator, heating of the boiler-absorber 11 is interrupted and the latter is cooled during what is known as the absorbing period of the unit to effect evaporation of the refrigerant liquid in the evaporator 14 and absorption of the vapor by the absorbent. As cooling means for the boiler-absorber 11, I have shown a secondary cooling system comprising a vaporization-condensation circuit 17 having a vaporization portion 18 in heat exchange relation with the absorbent chamber of the boiler-absorber and a condensation portion 19 provided with heat dissipation

pating fins and arranged in the duct F to be cooled by air. The cooling circuit 17 is charged with methyl chloride or other suitable heat transferring fluid capable of vaporizing in the vaporization chamber 18 and of liquefying in the condenser 19 and is provided with a motor-operated valve 20 for controlling the flow of liquid from the condenser to the vaporization chamber and is also provided with a collecting vessel 21 for storing the liquid when the valve is closed.

The operation of the refrigerating unit on alternate generating and absorbing periods is controlled by a suitable change-over device 22 constructed and arranged to deenergize the heater 16 and simultaneously to energize the motor of the valve 20 to open the latter at the end of the generating period and to deenergize the motor of the valve 20 to close the latter and simultaneously to energize the heater 16 at the end of the absorbing period. For this purpose, the change-over device 22 includes a pair of levers 23 and 24 pivotally mounted as at 25 and operatively connected together by a toggle spring 26 to form a snap-action type control. The lever 23 carries a circuit-controlling contact 27 for cooperative engagement with one or the other of a pair of stationary contacts 29 and 30, respectively. Contact 29 is arranged on one side of the lever 23 and is connected by line 31 to the heater 16 which in turn is connected by line 32 to the positive line of the current source, while contact 30 is arranged on the opposite side of the lever 23 and is connected by line 33 to the motor of the valve 20 which in turn is connected by line 34 to the positive line of the current source.

The lever 24 is disposed between a pair of limiting stops or abutments 35 and 36 and is movable from one abutment to the other and vice versa by a reciprocatable rod 37 actuated by the expansible bellows 38 or other movable element of a thermostat responsive to the temperature of the boiler-absorber 11 by means of a thermostat bulb 39 and operating against a counterbalancing force provided by a spring 40. A centering spring 41 cooperates with the lever 24 to maintain the latter normally in engagement with one or the other of the abutments 35 and 36.

In this manner, the circuit-controlling lever 23 of the change-over device 22 will be shifted from one of its circuit-closing positions to the other with a snap-action at a critical temperature attained during the generating period of the unit respectively to interrupt operation of the heating means 16 and open the valve 20 to initiate operation of the cooling means 17 and will be shifted from its second-named to its first-named circuit-closing position with a snap-action at another critical temperature attained during the absorbing period of the unit respectively to initiate operation of the heating means 16 and close the valve 20 to terminate operation of the cooling means 17.

Inasmuch as the refrigerating unit produces refrigeration intermittently, that is, during the absorbing periods, the evaporator 14 may be associated with a brine tank or other well-known cold hold-over means arranged in the storage space 15 of the cabinet 10 so as to prevent or reduce the temperature fluctuations occasioned by the flow of comparatively warm refrigerant liquid to the evaporator during the generating periods of the unit.

In order to compensate for changes in the refrigeration demands, it is desirable to vary the rate of circulation per unit of time of the re-

frigerant through the system. For this purpose, I have shown as an example a rheostat 45 having a control arm 46 connected by line 47 to the negative line of the current source and movable across resistance 48 connected by line 49 to the contact 27 of the movable control lever 23 of the change-over device 22 so as to vary the heating rate of the heater 16 and, in consequence thereof, vary the rate of liberation per unit of time of the refrigerant from the absorbent during the generating periods of the unit.

The resistance 48 of the rheostat 45 is also connected by line 50 to a motor-driven fan assembly 51 associated with the duct F and operating to control the rate of flow of air over the condensers 12 and 19. In this manner, upon movement of the control arm 46 across the resistance 48, the operating speed of the motor-driven fan assembly 51 will be varied so as to vary correspondingly the capacity or output per unit of time of the condenser or heat dissipating part 12 for liquefying the refrigerant vapors during the generating periods and the capacity or output per unit of time of the secondary cooling system 17 for removing the absorption heat during the absorbing periods of the unit.

The rheostat 45 also controls the rate of energization or operating speed of another motor-driven fan assembly 52 arranged to circulate the air in the storage space 15 in heat exchange relation with the evaporator or cooling unit 14 so as to control the capacity or output of the latter per unit of time. The fan assembly 52 is connected by line 53—33 with the contact 30 of the change-over device 22 and by line 54 with the positive line of the current source so as to be energized during the absorbing periods of the unit.

Thus, the heating rate of the heater 16 controlling the rate of liberation per unit of time of the refrigerant vapors from the absorbent during the generating periods, the operating speed of the motor-driven fan assembly 51 controlling the rate of condensation per unit of time of said refrigerant vapors during the generating periods and the cooling rate per unit of time of the secondary cooling system 17 during the absorbing periods, and the operating speed of the motor-driven fan assembly 52 controlling the rate of circulation per unit of time of the air in the storage space 15 in heat exchange relation with the evaporator or cooling unit 14 are all controlled by the rheostat 45.

The control arm 46 of the rheostat 45 is actuated by the expansible bellows or other movable elements 55 and 56 of thermostats 57 and 58, respectively, the former responsive to the temperature in the storage space 15 of the cabinet 10 by means of a thermostat bulb 59 and the other thermostat responsive to the ambient air temperature by means of a thermostat bulb 60. Each of the expansible bellows 55 and 56 operates against a counterbalancing force or pressure provided by a spring or the like 61 adjustable by means of a nut 62 or other suitable means to set the desired operating temperatures of the respective thermostats 57 and 58.

The cabinet thermostat 57 is constructed and arranged to operate over a comparatively short range of temperatures corresponding to the temperature fluctuations in the storage space 15 while the room thermostat 58 is constructed and arranged to operate over a comparatively long range of temperatures corresponding to the temperature fluctuations of the ambient air and each thermostat operates within its respective temp-

erature range to effect movement of the control arm 46 across the resistance 48 between the points of highest and lowest resistance indicated as H and L, respectively.

Having described one embodiment of the invention, its operation is as follows:

With the temperature in the storage space 15 and the ambient air temperature at the levels for which the respective thermostats 57 and 58 have been set by the adjusting nut 62 so that the control arm 46 of the rheostat 45 occupies the point of highest resistance H on the resistance coil 48 as shown in Fig. 1, the heater 16 and the fan assembly 51 will be energized at a comparatively low rate during the generating periods of the unit and such fan assembly together with the fan assembly 52 will be energized at a comparatively low rate during the absorbing periods of the unit. Consequently, the refrigerant will be circulated through the system at a comparatively low rate per unit of time to take care of the heat leakage through the insulated walls of the cabinet 10. In other words, the unit will operate with comparatively long generating and absorbing periods.

Upon temperature rise in the cabinet, that is, the storage space 15, occasioned by opening the door of the cabinet or by placing more foodstuffs in the storage space to be cooled, the control arm 46 of the rheostat 45 will be moved by the expandible bellows 55 of the cabinet thermostat 57 across the resistance 48 toward the point of lowest resistance L to increase correspondingly the heating rate of the heater 16 and the operating speed of the fan assembly 51 during the generating periods of the unit and the operating speed of said fan assembly and that of the fan assembly 52 during the absorbing periods so as to increase the rate of circulation of the refrigerant per unit of time and restore the temperature in the storage space 15 to the desired level by shortening the cycles of the unit.

Likewise, upon a rising room or ambient temperature, the control arm 46 will be moved by the expandible bellows 56 of the room thermostat 58 across the resistance 48 toward the point of lowest resistance L to shorten the cycles of the unit and thereby increase the rate of circulation of the refrigerant per unit of time to take care of the increased heat leakage through the heat insulated walls of the cabinet.

The cabinet thermostat 57 and the room thermostat 58 may operate together to move the control arm 46 across the resistance 48 from the point of highest resistance to the point of lowest resistance or such thermostats may operate independently of one another depending upon the nature of the temperature changes, that is, whether occurring in the storage space 15 of the cabinet 10 in which event the cabinet thermostat 57 will operate, or whether occurring outside the cabinet in which event the room thermostat 58 will operate, or whether occurring both inside and outside the cabinet in which event both thermostats 57 and 58 will operate.

It will thus be seen from the foregoing that the heating rate of the heater 16 for that part of the refrigerating system in which the refrigerant is generated or liberated from the absorbent; the cooling rate of the cooling fluid for those parts of the system in which the refrigerant is liquefied and is absorbed, respectively, and the output per unit of time of that part in which the refrigerant is evaporated are all controlled in accordance with the refrigerating de-

mands, that is, in accordance with the temperature in the space being cooled and the temperature outside the said space so that upon change in any one or both of said temperature conditions, the capacity or output per unit of time of each of the parts of the refrigerating system will be altered automatically to effect circulation of the refrigerant at the requisite rate per unit of time to maintain the desired temperature in the space being cooled. In this manner, the highest coefficient of performance of the unit will be obtained during normal operating conditions and as such conditions prevail during the greater part of the operating time of the unit, the average coefficient of performance of the refrigerating unit will be comparatively high.

It may be desirable, especially where the evaporator or cooling unit of the refrigerating apparatus is constructed and arranged to cool an ice freezing or other low temperature chamber, to employ a third thermostat responsive to the temperature of such freezing chamber, or to the evaporator temperature, to actuate the rheostat or other control for the several overloading or capacity-varying means so as to compensate for temperature changes in said freezing chamber occasioned by placing water or comestibles therein to be frozen.

Such an arrangement is shown in Fig. 2 in connection with a pair of intermittent absorption refrigerating units A and B associated with a household refrigerator cabinet 110. Inasmuch as the refrigerating units are similar to one another, only the various parts of the unit A will be described in detail, it being understood that unit B has similar parts which for convenience have been designated by the same reference numerals used for the corresponding parts of unit A but distinguished therefrom by the addition of a prime.

As in the installation described in connection with Fig. 1, each unit comprises a closed system formed by a plurality of interconnected parts including a boiler-absorber or generator-absorber 111 containing strontium chloride or other suitable absorbent capable of absorbing ammonia or other refrigerating fluid employed in the system, a condenser 112 provided with heat dissipating fins and arranged in a flue space or duct F to be cooled by air, a receiving vessel 113 embedded in the thermal insulation of the cabinet 110, and an evaporator 114. However, in the present instance, the evaporator 114 has a cooling or evaporator part 90 in heat exchange relation with an ice freezing or low temperature compartment 91 in the cabinet 110 and has another cooling or evaporator part 92 preferably provided with cooling fins and arranged to cool the air in the storage space 115 of the cabinet. If desired, the freezing compartment 91 may be thermally insulated from the storage space 115 so as to reduce or prevent the heating up influence on the freezing compartment of the air in the storage space 115 inasmuch as the average temperature in the latter is higher than that maintained in the freezing compartment 91.

Each unit is provided with an electrical heating element 116 or other suitable heating means to supply the necessary heat to the boiler-absorber during the generating period to effect liberation of the refrigerant from the absorbent. The refrigerant vapors liberated during this period of the unit are condensed or liquefied in the condenser 112 under the cooling action of the

cooling air and the refrigerant liquid is collected in the receiver 113 and evaporator 114.

Each unit is also provided with suitable cooling means to cool the boiler-absorber during the absorbing period so as to effect evaporation of the refrigerant liquid in the evaporator and absorption of the vapor by the absorbent and thus produce refrigeration in the freezing compartment 91 and in the storage space 115 of the cabinet 110. For this purpose, I have shown a secondary cooling system 117 common to both units and comprising a vaporization condensation cooling circuit having a vaporization portion 118 in heat exchange relation with the absorbent chamber of the boiler-absorber 111 of unit A and a similar vaporization portion 118' in heat exchange relation with the absorbent chamber of the boiler-absorber 111' of unit B and a condensation portion 119 provided with heat dissipating fins and arranged in duct F to be cooled by air. The secondary cooling system 117 is charged with methyl chloride or other suitable heat transferring fluid capable of vaporizing in the vaporization chamber 118 or 118' and of liquefying in the condenser 119 and is provided with a motor-operated valve 120 for controlling the flow of liquid from the condenser 119 to the vaporization chamber 118 and with another motor-operated valve 120' for controlling the flow of liquid from the condenser 119 to the vaporization chamber 118'. The secondary cooling system is also provided with a collecting vessel 121 interposed in the circuit between the condenser 119 and the valves 120 and 120' at a suitable level with respect to the vaporization chambers 118 and 118'.

In the installation shown, the two units A and B operate in out-of-phase relation to one another so as to provide substantially continuous refrigeration for the ice freezing compartment 91 and for the air in the storage space 115, such operation being automatically controlled by a change-over device 122 having a pair of levers 123 and 124 pivotally mounted as at 125 and operatively connected together by a toggle spring 126 to provide a snap-action type control. The lever 123 carries a circuit closing contact 127 for cooperative engagement with a pair of contacts 128 arranged on one side thereof and with a similar pair of contacts 128' arranged on the opposite side thereof. One of the contacts 128 of one pair and one of the contacts 128' of the other pair are connected together by line 129. The other one of the contacts 128 of the first-named pair is connected by line 131 to the heater 116 which in turn is connected to the positive line of the current source and the aforesaid contact is also connected by line 133 to the motor of the valve 120 which is also connected to the positive line of the current source. The other one of the contacts 128' of the second-named pair is similarly connected to the heater 116' and the motor of the valve 120' by lines 131' and 133', respectively, each of which is connected to the positive line of the current source as shown.

The lever 124 of the change-over device 122 is disposed between a pair of limiting stops or abutments 135 and 136 and is movable from one abutment to the other and vice versa by the expandible bellows or other movable elements 138 and 138', respectively, of a pair of oppositely disposed thermostats, the former responsive to the temperature of the boiler-absorber 111 by means of thermostat bulb 139 and the other responsive to the temperature of the boiler-absorber 111'

by means of thermostat bulb 139'. A centering spring 141 cooperates with the lever 124 to maintain the latter normally in engagement with one or the other of the abutments 135 and 136.

5 In this manner, the circuit-controlling lever 123 of the change-over device 122 will be shifted from one of its circuit-closing positions to the other with a snap action at a critical temperature attained during the generating period of a respective unit to interrupt operation of the heating means and initiate operation of the cooling means of said unit and simultaneously interrupt operation of the cooling means and initiate operation of the heating means of the other unit for operation of said units in out-of-phase relationship with respect to one another.

As in the installation heretofore described in connection with Fig. 1, the rate of flow of air over the primary and secondary condensers in the duct F is controlled by a motor-driven fan assembly 151. Moreover, the operating speed of the fan assembly 151 together with the heating rate of the heater 116 for the boiler-absorber 111 of unit A as well as the heating rate of the heater 116' for the boiler-absorber 111' of unit B are controlled by a rheostat 145 having a control arm 146 connected by line 147 to the negative line of the current source and movable across a resistance 148 connected by line 149 to the line 129 interconnecting one of the contacts 128 and one of the contacts 128' of the change-over device 122. The motor-driven fan assembly 151 is connected by line 150 to the line 129 and is also connected to the positive line of the current source so that the circuit is made through the rheostat 145.

The control arm 146 of the rheostat 145 is operatively connected to a reciprocatable rod 152 actuated by the expandible bellows or other movable elements 153, 154 and 155 of three thermostats 156, 157 and 158, respectively, the first being responsive to the temperature in the storage space 115 of the cabinet by means of thermostat bulb 159, the second being responsive to the temperature in the freezing compartment 91 of the cabinet by means of thermostat bulb 160, and the third being responsive to the ambient air temperature by means of thermostat bulb 161. Each of the expandible bellows 153, 154 and 155 operates against a counterbalancing force or pressure provided by a spring 162 adjustable by means of nut 163 to set the operating temperatures of the respective thermostats 156, 157 and 158.

The thermostats 156, 157 and 158 are set to operate at respectively different temperatures corresponding respectively to the normal temperatures in the storage space 115, the freezing compartment 91 and the ambient air and are constructed and designed to operate over respectively different ranges of temperatures corresponding respectively to the temperature fluctuations in the storage space 115, the freezing compartment 91 and the ambient air. Moreover, each of the aforesaid thermostats is constructed and designed to operate within its respective temperature range to effect movement of the control arm 146 of the rheostat 145 across the resistance 148 between the point of highest resistance H and the point of lowest resistance L.

70 The operation of this embodiment of the invention will be obvious from the foregoing description together with the previous description in connection with Fig. 1, it being evident that the heating rate of the heating means for the boiler-absorber of each unit, the cooling rate of

the cooling means for the primary condenser of each unit and the cooling rate of the cooling means for the boiler-absorber of each unit will all be varied automatically upon temperature change of the ambient air, or in the storage space 115, or in the freezing compartment 91 to compensate for such temperature variations. Consequently, the refrigerating apparatus will have its highest coefficient of performance when operating under normal conditions or loads to meet the normal refrigeration demands. 10

Instead of having the room or ambient thermostat operate independently of the cabinet thermostat and/or the evaporator thermostat to actuate the movable element of the rheostat or other device controlling the heating rate of the heating means for that part of the refrigerating system in which the refrigerant is liberated and the cooling rate of the cooling means for those parts of the refrigerating system in which the refrigerant is liquefied and is absorbed, respectively, it may be desirable and advantageous to have the cabinet thermostat or the evaporator thermostat selectively control the heating rate of said heating means and the cooling rate of said cooling means between a predetermined minimum and an increased value determined by the room thermostat.

Such an arrangement is shown in Fig. 3 in connection with refrigerating apparatus similar to that heretofore described in connection with Fig. 2 and in which the same reference characters have been used to designate like parts in both figures.

In this embodiment of the invention, the heating rate of the heating means of each unit and the operating speed of the motor-driven fan assembly 151 controlling the capacity or output per unit of time of the primary condenser of each unit and the capacity or output per unit of time of the secondary cooling system are all varied by means of a rheostat or other suitable device 180. The control arm 181 of the rheostat 180 is connected by line 182 to the negative line of a current source and is movable across a resistance 183 between the point of highest resistance H and the point of lowest resistance L by the expansible bellows or other movable element 184 of a thermostat 185 responsive to the ambient air temperature by means of thermostat bulb 186. The expansible bellows 184 operates against a counterbalancing force provided by a spring 187 which sets the operating temperature of the thermostat 185.

Instead of being connected directly to the line 129 interconnecting one of the contacts 128 and one of the contacts 128' of the change-over device 122 as heretofore described in connection with Fig. 2, the resistance 183 is connected by line 188 to one of a pair of stationary contacts 189 arranged adjacent one side of the movable lever 190 of a circuit-controlling switch 191. The other one of the pair of contacts 189 is connected by line 192 to the line 129 interconnecting one of the contacts 128 and 128' of the change-over device 122. Thus, the circuit through the rheostat 180 for the heaters 116 and 116' and the motor-driven fan assembly 151 is made by way of the switch 191.

Lever 190 is pivotally mounted as at 193 and is operatively connected by a toggle spring 194 to another pivoted lever 195 so as to provide a snap-action type switch. The lever 190 carries a circuit-closing contact 196 for cooperative engagement with the aforesaid pair of contacts 189

arranged on one side thereof and also for cooperative engagement with another pair of contacts 197 arranged on the opposite side thereof. One of the contacts 197 is connected by line 198 to a resistance 199 in the negative line of a current source while the other one of the contacts 197 is connected by line 200 to line 192 leading to the switch contacts 128 and 128' of the change-over device 122 to provide another circuit for the heaters 116 and 116' and for the motor-driven fan assembly 151 by means of which said parts are energized at a predetermined minimum rate per unit of time.

The lever 195 of the switch 191 is arranged between a pair of limiting stops 201 and 202 and is movable from one abutment to the other and vice versa by the expansible bellows 203 of a thermostat 204 responsive by means of thermostat bulb 205 to a cabinet temperature affected by the evaporator of each unit. The expansible bellows 203 operates against a counterbalancing force provided by a spring or the like 206 so as to effect movement of the lever 195 within the limits of the stops 201 and 202 over a predetermined range of temperatures and shift the circuit-controlling lever 190 of the switch 191 from one of its circuit-closing positions to the other with a snap-action at one predetermined cabinet or evaporator temperature and shift said lever from its second to its first-named circuit-closing position at another predetermined cabinet or evaporator temperature.

As in the installations previously described, the cabinet thermostat 204 is constructed and designed to operate over a comparatively short range of temperatures corresponding to the usual temperature fluctuations in the cabinet 110 while the room thermostat 185 is constructed and designed to operate over a comparatively long range of temperatures corresponding to the room air temperature fluctuations in which the refrigerating apparatus is to be operated.

The operation of this embodiment of the invention is as follows:

With the cabinet or evaporator temperature at the desired level for which the thermostat 204 has been set so that the circuit-controlling lever 190 of the switch 191 occupies the position shown by the dot-and-dash line in the drawing to close the circuit through the resistance 199, the heaters 116 and 116' and the fan assembly 151 will be energized at a comparatively low rate during the generating periods of the respective units and said fan assembly will also be energized at a comparatively low rate during the absorbing periods of the respective units under control of the change-over device 122. Consequently, the refrigerant will be circulated through the respective systems at a comparatively low rate per unit of time corresponding to the normal operating conditions of the refrigerating apparatus.

Upon temperature rise in the cabinet or in the evaporator occasioned by opening the door of the cabinet or placing more foodstuffs in the storage space 114 to be cooled, or placing water or comestibles in the freezing compartment 91 to be frozen, or by rising room temperature which affects the rate of heat leakage through the insulating walls of the cabinet 110, the lever 195 of the switch 191 will be moved from its abutment 202 toward its abutment 201 by the expansible bellows 203 of the thermostat 204. When the aforesaid lever 195 moves past dead center of the switch 191, the lever 190 will be shifted with a snap-action by the toggle spring

11

194 to the position shown in full lines in the drawing to interrupt the circuit through the resistance 199 and to close the circuit through the rheostat 180 so as to energize the heaters 116 and 116' and the fan assembly 151 at an increased rate per unit of time determined by the ambient air temperature as affecting the position of the control arm 181 relative to the resistance 183.

As soon as the cabinet or evaporator temperature is restored to the predetermined level for which the thermostat 204 has been set so that the lever 196 has been moved from its abutment 201 toward its abutment 202 and has reached a position past dead center of the switch 191, the lever 190 will be shifted to its position shown by the dot-and-dash lines to interrupt the circuit through the rheostat 180 and close the circuit through the resistance 199 to energize the heaters 116 and 116' and the fan assembly 151 at a comparatively low rate per unit of time during the generating periods of the respective units and energize said fan assembly at the aforesaid comparatively low rate per unit of time during the absorbing periods of the respective units.

Thus, the cabinet thermostat 204 operates to vary the heating rate of the heaters 116 and 116' and the operating speed of the fan assembly 151 between a predetermined minimum through resistance 199 and a variable maximum through rheostat 180 in accordance with the temperature conditions in the cabinet 110 and the room thermostat 186 operates to determine the value of said maximum heating rate of the heaters 116 and 116' and such maximum operating speed of the fan assembly 151 in accordance with the ambient air temperature. Consequently, as in the installation previously described, the refrigerating apparatus will have its highest coefficient of performance when operating under normal conditions and as such conditions will be prevalent for the greater part of the operating time of the refrigerating apparatus, the average coefficient of performance of the machine will be comparatively high.

It will thus be seen from the foregoing description of the fundamental principle underlying the invention that I have provided a new and improved control for absorption or adsorption type refrigerating apparatus by means of which not only the heating rate per unit of time of the heating means for that part of the refrigerating system in which the refrigerant is generated but also the cooling rate per unit of time of the cooling means for that part of the refrigerating system in which the refrigerant is liquefied; and/or the rate of heat transferred per unit of time between that part of the refrigerating system in which the refrigerant is evaporated and the space being cooled; and/or the cooling rate per unit of time of the cooling means for that part of the refrigerating system in which the refrigerant is absorbed or adsorbed and as a consequence the capacity or output per unit of time of each of said parts will be varied automatically in accordance with the demands for refrigeration.

Although I have shown and described the invention in connection with an electrical control for varying the capacity or output per unit of time of the several parts of the refrigerating apparatus, it will be obvious to those skilled in the art that the invention can be practiced by any other well known type of control. Therefore, it is to be understood that the invention is not intended to be confined to the particular type

12

of control illustrated except as limited by the appended claims.

While I have shown and described the invention in connection with intermittent absorption refrigerating apparatus, the same is equally applicable to absorption refrigerating apparatus of the continuous type and is also equally applicable to adsorption refrigerating apparatus. Consequently, it is to be understood that the use of the expressions "absorb," "absorbent," "absorption," etc. in the foregoing specification and in the following claims is intended to include the corresponding expressions applicable to adsorption refrigeration.

From the foregoing it is believed that the construction, operation and advantages of the invention will be readily understood by those skilled in the art without further description, it being borne in mind that numerous changes may be made in the details disclosed without departing from the spirit of the invention as set out in the following claims.

What I claim is:

1. Absorption type refrigerating apparatus including a generator-absorber, an air-cooled condenser, and an evaporator arranged to form a closed system for circulation of a refrigerating fluid; heating means for said generator-absorber; a vaporization-condensation circuit for cooling said generator-absorber having a vaporization portion in thermal exchange relation with the generator-absorber and a condensation portion cooled by air; a valve in said circuit for controlling the flow of liquid from said condensation portion to said vaporization portion; means cooperating with said valve and heating means for controlling the alternate heating and cooling of said generator-absorber; means for varying the heating rate of said heating means; means for varying the rate of flow of air over said condenser and said condensation portion; and means for controlling said first-named and second-named rate-varying means in accordance with a plurality of temperature conditions including one affected by said evaporator, and another affected by temperature of cooling air for said condenser and said condensation portion.

2. Absorption type refrigerating apparatus including a generator-absorber, an air-cooled condenser, and an evaporator arranged to form a closed system for circulation of a refrigerating fluid; heating means for said generator-absorber; a vaporization-condensation circuit for cooling said generator-absorber having a vaporization portion in thermal exchange relation with the generator-absorber and a condensation portion cooled by air; a valve in said circuit for controlling the flow of liquid from said condensation portion to said vaporization portion; means cooperating with said valve and heating means for controlling the alternate heating and cooling of said generator-absorber; means for varying the heating rate of said heating means; means for varying the rate of flow of air over said condenser and said condensation portion; and means responsive to a plurality of temperature conditions including a temperature affected by said evaporator, the temperature of cooling air for said condenser and said condensation portion, and the temperature of said evaporator constructed and arranged to control said first-named and second-named rate-varying means in accordance with change in any one of said temperature conditions.

3. A refrigerating system comprising a refrig-

erant vapor-supplying means, an ambient air-cooled condenser, a refrigerating evaporator, connections providing communication between said vapor-supplying means, condenser and evaporator, a heater for said vapor-supplying means, control means for varying the heating rate of said heater, means for varying the capacity of said condenser, thermostatic means responsive to a temperature condition affected by said evaporator, thermostatic means responsive to ambient air temperature, and operating means responsive to both thermostatic means capable of controlling both said heat-varying means and said condenser capacity-varying means.

4. Apparatus according to claim 3 in which one thermostatic means is responsive to ambient air temperature, the other thermostatic means is responsive to the evaporator temperature, and a third thermostatic means is provided responsive to the temperature of the air refrigerated by said evaporator, said operating means being responsive to all three thermostatic means.

5. Apparatus according to claim 3 further provided with refrigerated air circulating means for varying the rate of flow of air in thermal exchange relation with the evaporator, one of said thermostatic means being responsive to ambient air temperature, the other of said thermostatic means being responsive to the evaporator temperature, and thermostatic means being provided responsive to the temperature of the air circulated in contact with the evaporator, said operating means being responsive to all three thermostatic means and being capable of controlling said heat-varying means, said condenser capacity-varying means and said refrigerated air circulating means.

6. Apparatus according to claim 3 in which the refrigerant vapor-supplying means is a generator-absorber and the apparatus is provided with cooling means for the generator-absorber capable of being controlled so as to vary the cooling effect of said cooling means, said cooling means being controlled by said operating means.

7. Apparatus according to claim 3 further provided with a second refrigerant vapor-supplying means, a second ambient air-cooled condenser, a second refrigerating evaporator, and a change-over device capable of effecting heating of each of said vapor-supplying means intermittently and in out-of-phase relation to one another.

8. Apparatus according to claim 3 in which the control means for varying the heating rate of the heater comprises two control elements, one of said elements effecting operation of the heater

at a uniform rate equivalent to the normal refrigeration demand of the system and the other element effecting variable operation of the heater responsive to said thermostatic means, a change-over device being provided which is responsive to operation of at least one of said thermostatic means and capable of establishing control of the heater by said variable control element upon an increase in refrigeration demand on the system.

9. In absorption refrigerating apparatus comprising a generator-absorber capable when heated of liberating warm refrigerant vapor and when subsequently cooled of absorbing refrigerant vapor, heating means capable of supplying sufficient heat to the generator-absorber to effect liberation of refrigerant vapor therefrom, a condenser disposed in a cooling medium and capable of cooling the warm refrigerant vapor liberated from the generator-absorber and thereby effecting condensation of said vapor to the liquid state, and an evaporator disposed in a space to be refrigerated and serving as a receiver for liquid refrigerant capable of effecting refrigeration upon evaporation of liquid refrigerant therefrom as the evaporated refrigerant vapor is absorbed by the generator-absorber, the improvement which comprises heat control means capable of regulating the rate of heat input from said heating means to the generator-absorber, circulating means capable of effecting controlled circulation of the condenser cooling medium about the condenser, thermostatic means responsive to the temperature of the condenser cooling medium, thermostatic means responsive to the temperature within the refrigerated space, and interconnecting means capable of combining the responses from said thermostatic means in such manner as to provide a single response output upon a change in refrigeration demand, the heat control means and the circulating means being operatively associated with and controlled by said single response output of the interconnecting means.

NILS ERLAND AF KLEEN.
